ADJUSTABLE BLEACHER SEAT

Alfred J. Conn, Chicago, Ill., assignor, by mesne assignments, to Barber-Colman Company, Rockford, Ill., a corporation of Illinois

Application June 5, 1957, Serial No. 46,484

Term of patent 14 years

(Cl. D15—8)

FIG. 2FIG. 3FIG. 4Fig. 1 is a perspective view of an adjustable bleacher seat in position for use and showing my new design with portions of the figure broken away to indicate indeterminate length;

Fig. 2 is a side view thereof;

Fig. 3 is a side view of the article in its folded position; and

Fig. 4 is a fragmentary front elevational view of the article in its folded position.

Dotted lines in Figs. 2 and 3 representing wall and floor portions are for illustrative purposes only.

I claim:

The ornamental design for an adjustable bleacher seat, as shown and described.
